SHEET FEEDER

Application filed April 13, 1928. Serial No. 269,737.

The present invention relates to means for feeding sheets, and in its preferred embodiment is for delivering sheets from a pile.

The object is to provide mechanism of a simple, compact and effective nature for delivering the sheets successively, and materially lessening the danger of two or more sheets being fed simultaneously.

The preferred embodiment of the invention is illustrated in the accompanying drawings, wherein

Figure 1 is a side elevation of the feeder.
Figure 2 is a top plan view of the same.

Figure 3 is a longitudinal sectional view 15 on an enlarged scale.

Figure 4 is a detail sectional view through the suction head.

Figure 5 is a sectional view on the line 5—5 of Figure 4.

Figure 6 is a rear side elevation of the suction head and conduit connected thereto.

Figure 7 is a plan view of the detent finger for buckling the sheets.

Figure 8 is a detail side elevation of the 25 cam mechanism and associated parts.

Figure 9 is a view of the same at right angles to that shown in Figure 8.

Figure 10 is a detail view showing the operating mechanism for the suction head 30 supporting means.

Figure 11 is a similar view of the actuating means for oscillating the suction head.

Figure 12 is a similar view of the valve actuating means.

Figure 13 is a similar view of the detent and feeler actuating means.

Figure 14 is a similar view of the means for raising and lowering the idler presser rollers.

40 Figures 15-19 inclusive are detail views indicating the various positions assumed by the feeder head.

In the embodiment disclosed, a supporting frame is provided, comprising a base 45 20, having standards 21 and overhanging heads 22. Between the base and the heads are vertical guide standards 23, on which are slidably mounted sleeves 24 carrying oppositely outstanding arms 25. On these 50 arms is a table 26 that supports the pile of

sheets, shown in certain of the views, at 27.

To the overhanging heads 22 are secured brackets 28 provided with journal boxes 29, in which shafts 30 are rotatably mounted. These shafts carry sprocket wheels 31 over which pass sprocket chains 32 secured to the sleeves 24, and preferably provided on their outer free ends with counterweights 33. The shafts 30 furthermore are provided with worm wheels 34 in mesh with worms 35 carried by a cross shaft 36. Mounted on the front end of said cross shaft 36 is a ratchet wheel 37 and journaled on said shaft 36 alongside the ratchet wheel is an unbalanced pawl carrier 38. A pawl 39, 55 pivoted on the upper end of the pawl carrier, cooperates with the teeth of the ratchet wheel. The lower end of this pawl carrier is provided with a pin 40 located in the slot 41 of a pitman 42 that terminates 60 in a strap 43 surrounding an eccentric 44. The eccentric is carried by a drive shaft 45 journaled in the front side of the frame.

The pawl carrier 38 has a stop shoulder 46 on its rear side, and this stop shoulder 75 is adapted to be engaged by the upper end of a swinging detent 47 pivoted between its ends, as shown at 48 and having an extensible link connection 49 with the lower end of an actuating crank arm 50 carried by a 80 rock shaft 51. The rock shaft 51 extends across the frame above the table 26, and has adjustably mounted on it an arm 52 terminating in a feeler roller 53 that overlies the rear margin of the table 26. The 85 drive shaft 45 is provided with a cam 54 fixed thereto, and resting against said cam is a roller 55 carried by an arm 56 secured to the rock shaft 51. Obviously therefore on each rotation of the drive shaft 45, the 90 shaft 51 is rocked, thereby first raising the feeler 53, withdrawing the detent 47 from a position beneath the stop shoulder 46 and thereafter lowering the feeler 53 and returning the detent 47.

Extending across the frame is another rock shaft 57 having fixed thereto spaced rearwardly extending crank arms 58. In these crank arms is journaled a third rock shaft 59 that has fixed thereto but adjustable 100

along the same, an oscillatory suction head 60. A cam 61, fixed to the drive shaft 45, has riding on its periphery a roller 62 carried by the end of a crank arm 63 fixed to the rock shaft 57. Obviously therefore as the shaft 45 rotates the arms 63 will swing back and forth, thereby rocking the shaft 57 and raising and lowering the rock shaft 59 and the suction head 60.

10 The suction head 60 is arcuate in form with a curved active face 64, through which, as shown in Figures 4, 5 and 6, extend sets or rows of inlet ports 65, each row or set leading to a transverse passageway 66 that opens through one end face of the head. Yieldingly held against said end face by a spring 67 is an elbow 68, one end of which is journaled on the shaft 59, as shown at 69, the other end being carried by the rock 20 shaft, as shown at 70. In this elbow is a passageway 71 having an inlet port 72 surrounded by a packing gasket 73 and adapted to communicate with the successive passageways 66 as the suction head is swung or oscillated. The passageway 71 terminates in a nipple 74, to which is connected a flexible hose pipe 75 that leads to suitable means for creating suction, as for example, the inlet side of a pump.

30 The rock shaft 59, to which the suction head 60 is fixed, is provided at one end with a crank arm 76, and the free end of said crank arm is connected by a swinging link 77 to an actuating arm 78 journaled on the 35 rock shaft 57. This arm 78 carries a roller 79 that operates on the periphery of a cam 80 fixed to the drive shaft 45.

In the suction hose line 75 is a valve casting 81 containing a reciprocating plunger 40 valve 82 provided with a reduced portion 83 and a relief port 84. The valve 82 is connected by a link 85 with the lower end of a lever 86 fulcrumed between its ends, as shown at 87, the upper end of the lever having a roller 88 that rides on the periphery of a cam 89 fixed to the shaft 45.

Extending from the rear end of the frame is a supporting frame 90 forming part of a conveyor and guide. This conveyor includes 50 a front roller 91, a rear roller 92 and tapes 93 that pass about said rollers. The conveyor is driven by suitable means connected to a sprocket wheel or gear wheel 94 fastened to the rear end of the roller 91. At the 55 rear of the table 26 are vertical guide bars 95 and from the upper ends of said guide bars extend guides 96 that terminate over the roller 91. Over these guides 96 is located a transverse rock shaft 97, to which are fixed 60 crank arms 98 carrying a shaft 99 on which are adjustably mounted idler presser rollers 100 that are adapted to rest upon the roller 91. The rock shaft 97 is provided with a rearwardly extending actuating arm 101, on 65 the free end of which is located a roller 102

that rides on the periphery of a cam 103 fixed to the drive shaft 45.

70 Mounted on the upper end of one of the central guide bars 95 is a detent or sheet buckling finger 104. While this may be made in various ways the preferred form of structure is shown in Figure 7. It comprises a wire formed into a loop 105 and a forwardly extending finger 106 formed by an open reverse loop. Through the loop 105 is passed a fastener 107 that permits the adjustment of the finger forwardly or rearwardly. This finger is preferably located directly adjacent to the suction head 60.

75 The operation of the mechanism is substantially as follows: Assuming the apparatus in operation and the drive shaft 45 constantly rotated. With the top of the pile of sheets 27 at the desired elevation, the various cams above described and shown in detail in Figures 10-14 cause the following movements and operations in substantially the sequence given. With the suction head 60 elevated and the suction through the conduit 75 cut off to said suction head by the valve 82 being in its closed position, the cam 61 moves to a position to permit the suction head to lower on to the uppermost sheet of the pile, thereupon the cam 89 moves to a position to open the valve 82 and suction

80 will be created through the lowermost inlet ports 65. The sheet is thereby drawn against the lowermost portion of the peripheral face 64 of the suction head. The cam 61 now has moved to a position to raise the suction head, carrying the attached rear end of the sheet with it. The rear edge of the sheet is, however, under the detent or buckling finger 106, as a consequence of which said rear end is drawn around the finger 106 and the sheet is caused to buckle or bend, thereby breaking it away from the underlying sheet and materially lessening the danger of said underlying sheet being raised with it. When the attached sheet is thus elevated above the finger, 85 the suction head 60 begins to rotate rearwardly by reason of the cam 80 acting on the arm 78, and thus through the link 77 and crank arm 76, turning the rock shaft 59, to which the suction head 60 is attached. The sheet is thus fed rearwardly. During this 90 movement the cam 103 operates on the arm 101, thus turning the rock shaft and raising the presser rollers 100 away from the conveyor roller 91, leaving an open space into 95 which the rear end of the sheet enters on to the conveyor tapes. The suction head 60, having completed its turning movement, the cam 89 operates to again close the valve 82, cutting off suction from the suction head, and cam 103 turns to permit the rollers 100 to drop upon the sheet, which is now on the conveyor roller 91. Said sheet is thus drawn 100 onwardly by the conveyor and off of the pile. The mechanism is now in the initial condi-

100 105 110 115 120 125 130

tion above described, and the operation is repeated.

During these movements, the cam 54 is constantly rotating, allowing the feeler 53 to periodically drop on the top of the pile of sheets and alternately raising the same therefrom as a sheet is fed from the top. As long as the top is at the desired height and the feeler has a very restricted movement, it will not allow a sufficient movement of the rock shaft 51, the crank arm 50, the link 49 and the detent 47 to move from under the stop shoulder 46 of the pawl carrier, and consequently said pawl is not allowed to gravitate sufficiently to carry the pawl 39 over a tooth of the ratchet wheel 37, but as the top of the pile lowers due to the removal of the sheets therefrom, the feeler drops farther and farther downwardly until finally the detent 47 is out of the path of the shoulder 46. Therefore as the eccentric 44 rotates and the link 42 moves forwardly, the pawl carrier is permitted to have a sufficiently free movement to carry the pawl behind one or more of the teeth of the said ratchet wheel, and on the return movement of the link 42 under the action of the eccentric 44, the pawl carrier is positively moved in the opposite direction, thus turning the wheel and elevating the table. This movement continues until the feeler 53 is prevented from dropping and the detent 47 is again placed under the stop shoulder 46.

From the foregoing, it is thought that the construction, operation and many advantages of the herein described invention will be apparent to those skilled in the art, without further description and it will be understood that various changes in the size, shape, proportion and minor details of construction may be resorted to without departing from the spirit or sacrificing any of the advantages of the invention.

What I claim, is:

1. In a sheet feeder, the combination with a support for the sheets, of a rock shaft thereon, crank arms carried by the rock shaft, a second rock shaft journaled on the crank arms, an oscillatory suction head carried by the second rock shaft, a drive shaft having cam mechanism, an actuating arm fixed to the first rock shaft and operated by the cam mechanism, a crank arm on the second rock shaft, an actuating arm journaled on the first rock shaft and connected to the crank arm of the second rock shaft, and means for swinging the actuating arm from the cam mechanism.

2. In a sheet feeder, the combination with a pile supporting table, of a rock shaft journaled above the same and having crank arms, a second rock shaft journaled in the crank arms, an oscillatory suction head mounted on the second rock shaft, a crank arm fixed to the first rock shaft, an actuating arm

fixed to the second rock shaft, an actuating arm journaled on the first rock shaft and pivotally connected to the crank arm of the second rock shaft, a drive shaft, and cams carried by the drive shaft and operating on the actuating arms.

3. In a sheet feeder, the combination with a support for the sheets, of an oscillatory suction head thereon, means for raising and lowering the head and causing its oscillatory movement, a suction conduit connected to the suction head, a valve in said conduit, and means for opening the conduit when the head is lowered, holding it open during the elevation of the head and during its movement in one direction and thereafter closing said valve and holding it closed during the movement of the head in the opposite direction.

4. In a sheet feeder, the combination with a pile supporting table, of a rock shaft journaled above the same and having crank arms, a second rock shaft journaled in the crank arms, an oscillatory suction head mounted on the second rock shaft, a crank arm fixed to the first rock shaft, an actuating arm fixed to the second rock shaft, an actuating arm journaled on the first rock shaft and pivotally connected to the crank arm of the second rock shaft, a conduit connected to the suction head, a controlling valve in the conduit, a drive shaft, and cams carried by the drive shaft and operating the actuating arms and the valve in timed relation.

5. In a sheet feeder, the combination with a pile supporting table, of a roller suction head movable toward and from the pile, and having a swinging movement on a pivot axis that moves with the head toward and from the pile, a suction conduit connected to the head and having a controlling valve, a conveyor for receiving the sheets fed by the head, an idler presser roller movable toward and from the conveyor, and driving mechanism including cams that effect the raising and lowering of the suction head and its swinging movement, the operation of the valve and the said movement of the presser roller in timed relation.

6. In a sheet feeder, the combination with a pile supporting table, of a roller suction head movable toward and from the pile and having a swinging movement on a pivot axis that moves with the head toward and from the pile, a suction conduit connected to the head and having a controlling valve, a conveyor for receiving the sheets fed by the head, an idler presser roller movable toward and from the conveyor, a driving shaft, and cams fixed to the shaft in predetermined relation to effect the raising and lowering of the suction head and its swinging movement, the operation of the valve and the said movement of the presser roller in timed relation.

7. In a sheet feeder, the combination with a pile supporting table, of a rock shaft having crank arms, a second rock shaft journaled on the crank arms, an oscillatory suction head carried by the second rock shaft, a suction conduit connected to the suction head, a valve in the suction conduit, a driving shaft, cams on the driving shaft, and arms operated by the cams and actuating the various rock shafts and the valve in timed relation.

8. In a sheet feeder, the combination with a pile supporting table, of a rock shaft having crank arms, a second rock shaft journaled on the crank arms, an oscillatory suction head carried by the second rock shaft, a suction conduit connected to the suction head, a valve in the suction conduit, a conveyor for receiving the sheets fed by the suction head, a rock shaft, an idler roller carried by the rock shaft and movable thereby into and out of coaction with the conveyor, a driving shaft, cams on the driving shaft, and arms operated by the cams and actuating the various rock shafts and the valve in timed relation.

In testimony whereof I affix my signature.

ALBERT BROADMEYER.
